DESIGN FOR A PRINTED TEXTILE FABRIC OR SIMILAR ARTICLE OF MANUFACTURE

Murray Kay, New York, N. Y., assignor to Fur
Resembling Fabrics Co., Inc., New York, N. Y., a corporation of New York

Application May 9, 1936, Serial No. 62,566

Term of patent 14 years

To all whom it may concern:

Be it known that I, Murray Kay, a citizen of the United States of America, residing in the city of New York, county of New York, State of New York, have invented a new, original, and ornamental Design for a Printed Textile Fabric or Similar Article of Manufacture, of which the following is a specification, reference being had to the accompanying drawing, forming part thereof and showing in reduced dimensions a face view of a piece of textile fabric embodying my design.

The characteristic feature of the design resides in units each consisting of a single simulated pelt, the areas of one unit merging into the areas of the adjacent units in regular succession.

I claim:

The ornamental design for a printed textile fabric or similar article of manufacture as shown and described.

MURRAY KAY.
